UNITED STATES PATENT OFFICE.

HERBERT H. BUFFUM, OF WHITMAN, MASSACHUSETTS.

MACHINE FOR SEWING SHOES.

SPECIFICATION forming part of Letters Patent No. 410,145, dated September 3, 1889.

Application filed February 25, 1889. Serial No. 301,071. (No model.)

To all whom it may concern:

Be it known that I, HERBERT H. BUFFUM, of Whitman, county of Plymouth, and State of Massachusetts, have invented an Improvement in Sewing-Machines, of which the following description, in connection with the accompanying drawings, is a specification, like letters on the drawings representing like parts.

10 My invention relates to a sewing-machine of the kind known as the "McKay sewing-machine;" and it consists mainly in the novel construction of the horn and mechanism co-operating therewith for controlling the thread and operating the whirl that lays the thread 15 into the hook of the needle, and also in the means employed for waxing the thread.

In the McKay sewing-machine the shoe is supported right side out upon a horn through 20 which the thread is carried to the point where the stitch is formed, said horn containing at its tip and directly under the needle a device called the "whirl," which rotates or oscillates at each stitch, so as to lay the thread into the 25 hook of the needle, which is forced down through the sole and edge of the upper of the shoe, so that on the return or outward movement of the needle the thread is drawn out from the upper and sole in the 30 form of a loop, which is drawn through the loop formed in a similar manner at the preceding stitch, thus en chaining the thread at the outside of the sole. As the sole and the upper are temporarily connected before being 35 sewed on machines of this kind, the horn or shoe-support has to be inclined at an angle of about forty-five degrees to the axis of the needle in order to reach forward to the toe part of the sole while it is in the inside of 40 the upper, and in the machines as usually constructed the entire upwardly-extending part of the horn has been inclined at said angle, the base of the horn being pivoted in line with the axis of the needle, and extending 45 horizontally outward from its axis, and then diagonally upward to its tip, which is at a point just below the end of the needle. Such construction is objectionable, as in sewing around the extreme toe portion of the 50 shoe the heel end has to be lowered, so as to bring the sole portion nearly to the same angle as the horn, and the upper edge of the

counter or heel-stiffener is thus pressed down against the horn, and is frequently broken down, so as to injure the quality of the shoe. 55 An attempt has been made to obviate this objection by slightly depressing the back of the horn at the part where the edge of the counter comes when the heel portion of the shoe is depressed; but the internal thread-controlling or whirl-operating mechanism has heretofore been so constructed as to prevent a sufficient depression of the horn to obviate the objections just referred to, so that such expedient only diminishes the evil effects to a certain 60 extent without wholly obviating or removing them.

The object of the present invention is to produce a horn that will properly support the inner surface of the sole at all points while 70 being sewed without interfering with the upper, and which will permit the heel end of the shoe to be depressed as far as required without bringing the edge of the counter or heel-stiffener against the horn. To accomplish 75 this result, the horn extends diagonally downward from its tip at about the usual angle, but for a distance slightly less than the length of the shoe to be sewed, and then inclines downward in the opposite direction, so that 80 its base is nearly over the axis about which the horn revolves, said horn thus making an angle about midway of its height. The whirl at the tip of the horn is of the usual construction, consisting of a ring through which the 85 point of the needle descends, said ring being provided with an eye, through which the thread is passed, and with beveled gear-teeth meshing with a beveled pinion at the end of a shaft extending through the horn. The 90 said shaft in accordance with this invention terminates at the angle midway in the length of the horn, and is connected with another shaft which extends down to the base of the horn, and is rotated by gearing connected with a 95 shaft extending through the axis of the horn, which shaft is itself actuated in unison with the needle-actuating mechanism at the head of the machine in the usual manner. The 100 said shafts, extending from the base to the tip of the horn, may be connected in any suitable manner, so that the lower one transmits rotating motion to the upper, they being shown in this instance as connected by a uni-

versal joint, which is found in practice to operate well for this purpose. The front or inner portion of the horn is provided with a movable covering-plate, which may be fastened in position to wholly inclose the mechanism, but may be easily swung aside to afford access to the said mechanism for the purpose of threading the machine, oiling the working parts, &c.

10 The invention further consists in various details of construction, which will be herein-after pointed out, and in appliances for waxing the thread and keeping the horn heated, so as to make the wax-thread pliable until 15 after the stitch is completed.

Figure 1 is a front elevation of a lower portion of a McKay sewing-machine provided with a horn embodying this invention; Fig. 2, a vertical section on line 2 2 of Fig. 3 20 through the wax-receptacle; Fig. 3, a vertical section on line 3 3 of Fig. 2 through the wax-receptacle; Fig. 4, a longitudinal section of the horn, showing the inclosed mechanism and the wax-receptacle in side elevation; Fig. 5, 25 a plan view of the base portion of the horn and mechanism contained therein; Fig. 6, an enlarged longitudinal sectional detail of a portion of the horn and shaft that operates the whirl and devices for supporting and adjusting the same; and Fig. 7, a transverse section on line 7 7, Fig. 6.

The horn forming the subject of this invention is of proper size to be interchanged with the horns now commonly used in McKay sewing-machines, and is constructed to be operated by said machines without any change in the other parts, the said horn a , Fig. 1, being pivoted on the frame-work b , forming the base of the machine, so that it 35 revolves about an axis in a bearing at b^2 in line with the axis of the needle c , the actuating mechanism for which needle, together with the other co-operating devices at the top of the machine, are not shown, as they are of well-known construction. The said horn a extends downward diagonally from its tip opposite the needle for a certain distance, as shown at a^2 , so that its extremity may extend out inside the upper of the shoe toward the 40 toe portion thereof; but, instead of extending wholly down to the base at the same or substantially the same angle, the horn, in accordance with this invention, is turned about midway of its length and extends to the base 45 at an opposite inclination to the tip portion, as shown at a^3 , so that its base is nearly over the axis b^2 , about which the horn revolves in the manipulation of the machine. The inclined tip portion a^2 is shorter than the length 50 of the shoe, and by inclining the lower portion a^3 in the opposite direction a free space is left for the depression of the heel portion of the shoe, as indicated in dotted lines, Fig. 1, so that the shoe-sole can be brought down 55 nearly to the same inclination as the tip portion a^2 of the horn without crushing or bending the counter or heel-stiffener of the shoe,

as takes place when the entire horn is of the same inclination as the tip portion a^2 .

The tip of the horn is provided with a whirl d , Fig. 4, which co-operates with the thread and the needle c in the usual manner, making an oscillating movement at each stitch, so as to lay the thread e , which passes through the horn to the said whirl, into the hook of the needle c each time that the latter is forced down through the stock and through the central opening of the whirl d . The said whirl is toothed at its periphery and meshes with a pinion f , formed at the end of a shaft f^2 , extending through the tip portion of the horn and connected with a shaft g , provided at its lower end with a spur-wheel g^2 , meshing with an intermediate g^3 , itself meshing with another intermediate g^4 , that is in turn engaged and actuated by a spur-wheel g^5 , connected with a shaft g^6 , that extends down to a point near the lower portion of the frame b , (see Fig. 1,) where it is actuated by mechanism connected with the stitch-forming mechanism at the head of the machine in the usual manner, so that the said shaft g^6 makes an oscillating movement at the proper time with relation to each movement of the needle, and through the connecting mechanism just described also causes the whirl d to make an oscillatory movement, by which the thread is laid into the hook of the needle. The gearing $g^2 g^3 g^4 g^5$ is such that the revolution of the horn bodily about its axis at b^2 itself produces no rotation of the whirl d relative to the needle, so that the movements of said whirl are in the proper relation to the said needle in whatever position the horn may be in upon its axis.

105 The inner or concave side of the horn is provided with a cover a^4 , extending substantially from the base to the tip, and pivoted at a^5 (see Fig. 5) at one side of the base, so that it can be swung open like a door to afford access to the interior of the horn and working parts inclosed therein. The said cover when closed is fastened by a screw or other clamping device a^6 . (See Fig. 1.)

110 The gears $g^3 g^4 g^5$ are inclosed by a cap-plate h , (see Fig. 5,) which may be removed when the cover or door a^4 is open; but said cap-plate is provided with short tubes h^2 just above the bearings of the gear-wheels, so that the latter can be lubricated without removing 115 the cover h .

120 The shafts f^2 and g , that transmit the movement from the gearing at the base of the horn to the whirl, are shown in this instance as connected by a universal joint at i , each of 125 said shafts having forked ends i^2 and i^3 , each pivotally connected with an intermediate block i^4 , and the pivoted axes being at right angles. It is not essential, however, that the connection between the shafts should be a universal or gimbal joint, as there is no variation 130 in the angle between the two parts of the shaft in the operation of the machine, so that any connection by which one shaft may im-

part rotary motion to another at any angle to it may be used. The lower end of the shaft g has its bearing in a step-piece k , pivoted in a forked block k^2 , having a stem that is longitudinally movable and capable of swiveling in a bearing k^3 at the under side of the plate b^3 at the base of the horn which supports the gears g^2 g^3 g^4 g^5 . This construction enables the step-block k to be adjusted so as to make the gears g^2 g^3 mesh together properly, and when said step-block is in proper position it is secured by a clamp or set-screw k^4 , engaging the stem of the forked piece k^2 .

The shaft f^2 , that carries the pinion f , is made adjustable, so that said pinion may be made to mesh properly with the teeth of the whirl d , and the said shaft is supported in the horn as follows: The upper portion f^2 of the shaft works in a tubular bore in the tip piece a^7 of the horn and has its lower end enter within a bore in the lower portion f^3 (see Figs. 6 and 7) of said shaft, which is of larger diameter than the upper portion f^2 , said portion f^3 being made integral with the fork i^2 of the universal joint. The lower end of the portion f^2 is slotted or forked, as shown at f^4 , Fig. 6, and embraces a pin f^5 , passing transversely through the larger tubular portion f^3 of the shaft, so that the two parts of the shaft are fastened together for rotation, but the upper part is longitudinally adjustable in the lower part. The lower part f^3 has its bearings in a tubular bearing piece or sleeve m , and is prevented from longitudinal movement therein by engagement of the lower end of the sleeve with the shoulder formed at the junction of the shaft f^3 and fork i^2 , as will be understood from Fig. 6, and by engagement of the upper end of the sleeve with the hub or boss m^2 , keyed to the portion f^3 of the shaft by a transverse pin m^3 . The sleeve m itself is clamped between a projecting portion a^8 at the inside of the horn and a removable block a^9 , as best shown in Figs. 6 and 7, said block being screwed to the horn and the said bearing-sleeve m having a circumferential groove m^5 to receive the screws, as shown in Fig. 7. The sleeve m is thus prevented from rotating and forms the bearing for the portion f^3 of the shaft, while confining the same against longitudinal movement, and the inner bearing-surface of the sleeve m is lubricated through a passage m^6 in the back of the horn leading to a circumferential groove around the bearing-bushing, from which groove is a radial passage m^7 (see Fig. 6) into the bearing-surface.

In order to adjust the upper portion f^2 of the shaft longitudinally and to prevent further longitudinal movement after it has been properly adjusted, the said shaft is provided at its lower end with a hub n , having a circumferential flange n^2 , engaging a semi-circumferential groove in the hub or block m^2 , and thus preventing movement of the hub n along the shaft with relation to the hub m^2 and lower portion f^3 of the shaft, which has

no longitudinal movement. The shaft f^2 is fastened with relation to the hub n by a set-screw n^3 , and by loosening said set-screw the portion f^2 of the shaft may be adjusted longitudinally without disengaging its forked end from the pin f^5 , after which by tightening said set-screw n^3 further longitudinal movement of the portion f^2 of the shaft is prevented.

The horn is shown in this instance provided with means for waxing and guiding and controlling the thread to be used. The said thread, in the form of the usual ball, is placed in a receptacle o , (see Figs. 1 and 5,) fastened upon one side of the base of the horn, and the thread is passed through an opening in the cover of said receptacle into a waxing-receptacle, as shown in Fig. 2, the thread being lettered e in all the figures and its direction of movement toward the stitching-point being indicated by arrows where necessary.

The waxing-receptacle p is shown as made in a casting fastened to the main horn-casting near the base thereof, as indicated at p^2 , Figs. 4 and 5, the said receptacle consisting of a reservoir or chamber in the upper part of said casting, (best shown in Figs. 2 and 3,) the said reservoir being divided by a suitable partition p^3 , extending nearly to the bottom, into two parts, the part at one side of said partition containing a guide-wheel e^2 , over which the thread e is passed and by which the thread is caused to pass through the lowest part of the receptacle, so as to be immersed in the wax if there is any in the receptacle. The part of the chamber at the other side of the receptacle is provided with a hinged cover p^4 , which may be lifted at any time, as shown in dotted lines, Fig. 2, to replenish the wax, and the partition p^3 prevents the lumps of cold wax from coming against the wheel e^2 and thread, as it is only when the wax is melted and flows under the partition p^3 that it can reach the said wheel.

The portion of the receptacle containing the wheel e^2 is provided with a cover p^5 , which may be screwed in place, as shown in Fig. 4, as it does not need to be removed in the operation of the machine, and said cover supports a scraping device (best shown in Fig. 3) consisting of a stationary bar or blade r and a co-operating blade r^2 , supported from a rock-shaft or pivot r^3 , provided with an arm r^4 , acted upon by a spring r^5 , which tends to keep the blade r^2 down opposite the blade r , so as to scrape off the surplus wax as the thread passes up between the blades, as will be understood from Fig. 3. The spring r^5 permits the blade r^2 to yield against a knot or other enlargement of the thread, such knot raising the blade r^2 , as indicated in dotted lines, Fig. 3, and thus passing between the blades without causing the thread to break. After the thread passes through the clearing-blades r r^2 it is carried around a pulley e^3 , in order to enable its direction to be changed, and then passes through an auxiliary clearer

or rubber r^6 , which has further tendency to smooth down and even the wax upon it, after which the thread passes over the tension-wheel e^4 , which may be of usual construction, and from said tension-wheel it passes through an opening in the horn, as shown in Fig. 4, and then over a guide-pulley e^5 , supported on an arm or bracket rising from the gearing-covering plate h , and thence up through the horn, passing over a pulley e^6 on the cover portion a^4 of the horn at the angle in the horn, and thence up between the main portion and cover portion to the usual eye in the whirl d .

In order to obviate the necessity of passing the end of a new ball of thread into the waxing-receptacle and over the various guides when one ball is exhausted, the outer end of the ball is tied at the ball-receptacle o , as indicated at o^2 , Fig. 5, and consequently when the ball is exhausted the thread will break; but such breakage will invariably occur at the needle, as it will have a cutting action on the thread, and it will then be necessary merely to put a new ball in the receptacle o and tie the inner end thereof to the end of the twine that remains from the last ball, when the thread may be pulled through from the tip of the horn, the united ends passing through the various guides and blades without trouble until the end of the new ball of twine is brought up through the whirl ready for sewing.

The waxing-receptacle and horn may be heated sufficiently to keep the wax fluid in the receptacle and soft and pliable on the thread by means of a gas-flame when that is available; but, as shown in this instance, the horn is provided with a lamp t , which is made substantially T-shaped in plan extending across transversely under the wax-receptacle, as shown in Fig. 2, and also extending out beneath the base of the horn, as shown in Fig. 4, the said lamp being provided with two wick-tubes t^2 , the former terminating beneath the wax-receptacle and the latter beneath the plate b^3 at the base of the horn. There is sufficient space between the shell at the rear of the horn and the plates b^3 and h at either side of the shaft g to permit the heated products to rise up through the horn, and thus keep the entire horn warm up to the tip, where the stitch is made. A cover u , hinged at the back of the wax-receptacle, covers the thread and parts that co-operate with it as it passes from the wax-receptacle into the horn; but said cover may be raised, as shown in Figs. 4 and 5, when it is necessary to have access to the wax-clearers, &c.

A hand-lever w is provided for relieving the tension on the thread when it is desired to draw the thread out rapidly, said lever being pivoted at w^2 and provided with a cam-plate w^3 , (best shown in Fig. 5,) which acts on the stem of the part that applies the friction to the tension-wheel.

It will be seen that the thread-waxing ap-

pliances occupy a position with relation to the axis of the horn which is usually occupied by the horizontal arm that supports the base of the horn, and that the herein-described horn and whirl-operating mechanism in connection with the waxing appliances occupy but little if any more space and have but little if any more weight than the horn without waxing appliances heretofore commonly employed in machines of this class.

I claim—

1. In a machine for sewing boots and shoes, a pivotally-supported horn having its lower and upper portions inclined with relation to one another, a whirl at the tip of the horn, and actuating-shafts therefor in the upper and lower portions of the horn connected by a universal joint at or near the point where the inclination of the horn changes, a shaft extending through the axis of the horn, and gear-wheels g^2 g^3 g^4 g^5 , connecting the same with the whirl-operating shafts, substantially as described.

2. In a machine for sewing boots and shoes, a horn to support the sole inside the upper, said horn being inclined downward from its supporting-tip for a portion of its length and turned at an intermediate point at a different angle toward its base, and a movable cover for the inner or concave side of said horn, substantially as described.

3. The combination of a hollow horn having a closed space or chamber extending substantially from its base to its tip, the said horn being provided at its tip with a whirl and at its base with a dry thread and wax receptacle, with a heater having burners below the wax-receptacle and below the base of the horn, and thread-guides contained within the closed space in the horn, whereby the thread passes from the base to the tip of the horn through the interior of said closed space, substantially as described.

4. In a machine for sewing boots and shoes, a horn to support the sole inside the upper, having its upper and lower portions at an angle to one another, combined with a whirl and two actuating-shafts therefor in the upper and lower portions of said horn, respectively, said shafts having their axes inclined to one another and being connected at or near the angle of the horn, the upper one of said shafts being made in two parts, the lower portion of which is restrained from longitudinal movement by a bearing in the horn, and the upper portion of which is provided with a pinion meshing with the whirl and longitudinally adjustable in the lower portion, substantially as described.

In testimony whereof I have signed my name to this specification in the presence of two subscribing witnesses.

HERBERT H. BUFFUM.
